FREQUENCY MULTIPLIER

Edward L. Ginzton, Garden City, N. Y., assignor
to Sperry Gyroscope Company, Inc., a corpora-
tion of New York

Application January 13, 1944, Serial No. 518,054

21 Claims. (Cl. 172—281)

1

The present application relates to wave transmission apparatus and concerns particularly apparatus suitable for use in microwave systems.

An object of the invention is to provide methods and apparatus for frequency multiplication, particularly arrangements suitable for use in the microwave frequency spectrum.

A specific object of the invention is to provide a frequency doubler, and another object of the invention is to provide a frequency tripler.

Still another object of the invention is to provide a mixer multiplier.

It is an object of the invention to provide a stable crystal multiplier and to provide a multiplier having high efficiency at high frequency.

A further object of the invention is to provide methods and apparatus for avoiding burn-out of crystal multipliers.

Still another object of the invention is to provide a push-pull arrangement for improving the characteristics of crystals used for frequency multiplication.

Other and further objects and advantages will become apparent as the description proceeds.

In carrying out the invention in its preferred form, a pair of joined transmission lines is employed or a single transmission line is provided with input and output sections designed for different frequencies. Non-linear circuit means such as rectifying crystal means, for example, are interposed in one of the transmission lines designed for the lower frequency and serving as the input transmission line, or transmission line section. The output transmission line, or transmission line section, is coupled to the input transmission line, or transmission line section, and is preferably arranged to cut-off energy having a wavelength longer than the desired wavelength, in order to insure that the output frequency is substantially a pure harmonic of the input frequency.

A better understanding of the invention will be afforded by the following detailed description considered in conjunction with the accompanying drawings, in which

Fig. 1 is a side view, mainly in longitudinal section, of a frequency doubler;

Fig. 2 is another side view of the apparatus of Fig. 1 turned 90° from the position shown in Fig. 1;

Fig. 3 is a side view, mainly in longitudinal section, of a frequency tripler;

Fig. 4 is a fragmentary view of the apparatus of Fig. 3 including an output end view of the transmission line;

2

Fig. 5 is a longitudinal sectional view of a mixer multiplier;

Fig. 6 is a bottom view of the apparatus of Fig. 5;

Fig. 7 is a graph illustrating the characteristics of a square-law crystal rectifier of the type which may be employed in the apparatus of Figs. 1 to 6; and

Fig. 8 is a graph illustrating the composite characteristics of push-pull connected crystal rectifiers employed in the apparatus of Figs. 3 and 4.

Like reference characters are utilized throughout the drawings to designate like parts.

15 The frequency multiplier illustrated in the Figs. 1 and 2, comprises a transmission line 11 and a lateral transmission line 12 joined to the transmission line 11. In the arrangement as illustrated, the transmission line 11 is designed to receive the input or lower frequency, and the transmission line 12 is designed for supplying the output frequency, e. g. an even harmonic such as double frequency. As shown, the fundamental frequency transmission line 11 may be of the co-axial or concentric line type assumed to be circular in cross-section and the double frequency or second harmonic transmission line 12 may be of the wave guide type, shown in this case as a rectangular wave guide. To facilitate making the 20 requisite circuit connections to the transmission line 11, an input transmission line 13 may be provided for supplying the input energy, for example, ultra high frequency electromagnetic wave energy having a wavelength of approximately 10 centimeters in case a 5-centimeter wavelength output is desired.

The line 11 includes outer hollow cylinders 14 and 15 and an inner conducting rod 16. The outer hollow cylinders 14 and 15 are joined to and 25 extend laterally above and below the upper and lower surfaces of the rectangular wave guide 12, which have suitable openings for receiving the hollow cylinders 14 and 15. The inner rod 16 extends through the wave guide 12 and on either 30 side thereof.

For producing the desired second harmonic in the output, a non-linear circuit element 17 is interposed in the transmission line 11, for example, in series with the inner conductor rod 16. 35 In order to facilitate the mounting and replacement of the non-linear element 17, the hollow cylinder 14 and the rod 16 may be jointed so as to have physically separable portions 18 and 19, respectively. A conventional threaded coupling 40 21 is provided for joining the hollow cylindrical

members 14 and 18 and the rod portions 16 and 19 are suitably formed to make electrical connection with the terminals of the non-linear element 17.

The non-linear element 17 may take the form of a crystal rectifier unit of the type employed in microwave and other ultra high frequency radio receiving systems, for rectifying, detecting, or demodulating ultra high frequency energy. It is shown as a standard unit incased in a cylinder 22 with a downwardly extending pin terminal 23 and an upper flat contact terminal 24. The rod 16 is provided with a socket at the upper end to receive the pin terminal 23 and the rod 19 is provided with the contact button 25 at the lower end to make contact with the crystal terminal 24.

The input line 13 may also be a conventional coaxial line, including an outer cylinder 26 electrically and mechanically joined to the cylinder 18, and an inner conducting rod 27 electrically and mechanically connected to the inner conductor rod 19.

It will be understood that for the purpose of providing the requisite mechanical support for the inner conducting rod suitable low-loss insulators or bushings such as the element 28 may be provided.

Preferably biasing means are provided for causing the crystal rectifier 17 to operate in the more desirable portion of its characteristic curve. To this end, a source of biasing voltage such as a battery 29 may be provided which is electrically connected in series with the nonlinear crystal element 17. For example, the battery 29 may be provided with conductors 31 electrically connected to the inner rod 16 and the outer cylinder 18, the latter being electrically connected, in turn, to the wave guide 12, the outer cylinder 14, the outer cylinder 18 and the inner conducting rod 19. The coupling 21 serves to connect the hollow cylinders 14 and 18 electrically as well as mechanically, and the rod 19 and the cylinder 18 are electrically connected at their upper ends.

For the purpose of tuning the transmission line 11 and preventing reflections resulting in a high standing wave ratio, adjustable high frequency shorting plugs, or tuning elements 32 and 33 are provided. The tuning element 32 comprises an adjusting knob or handle 34 to which is secured a plug or annulus 35 of suitable conducting material, such as brass, which makes electrical contact with both the outer cylinder 18 and the inner rod 19. Pins 36 may be provided which are rigidly secured to the plug 35 and are slidably retained within an annular slot 37 in the knob 34. The knob 34 may be formed as a knurled ring-nut and the outer surface of the cylinder 18 may be threaded for engagement by the nut 34. The cylinder 18 is provided with slots 38 on both sides to receive the pins 36.

The lower tuning element 33 may be similarly constructed except that it includes a shorting plug 39 having an inner part 41 making electrical contact with the rod 16, an outer part 42 making electrical contact with the hollow cylinder 18, and a thin insulating band 43 of suitable low loss material, such as polystyrene tape, separating the parts 41 and 42 so as to form a condenser, the plates of which are the confronting surfaces of the members 41 and 42. Such a condenser serves as a high frequency short with respect to the alternating current input, but serves to insulate the rod 16 from the outer conductor 15 in order to provide a direct current circuit

for the biasing battery 29 and the crystal rectifier 17.

Suitable means are also provided for tuning the portion 44 of the wave guide 12, shown to the left of the transmission line 11. Such means may take the form of a conventional adjustable position plug 45, adjustably mounted by means of a screw 46 having a supporting block 47 and formed as a quarter-wave trap spaced from the inner surfaces of the wave guide 12.

The portion 48 of the wave guide 12 extending to the right of the transmission line 11 is broken away in Fig. 1 to simplify the drawings, but it will be understood that suitable connections by conventional choke couplings or the like, may be made between the output end 49 of the wave guide 12 and apparatus to which second harmonic wave energy is to be supplied.

The conversion of the fundamental frequency energy supplied through the transmission line 13 to the double frequency or second harmonic wave energy leaving the wave guide from the output end 49 results from the lack of linearity between voltage input and current output of the crystal rectifier 17.

The characteristic curve of such a crystal rectifier of the square-law type is shown in Fig. 7 in which current is measured along the vertical axis and voltage is measured along the horizontal axis. The magnitude of the biasing voltage in the battery 29 is so chosen as to accentuate the second harmonic. The exact amount of bias required will depend upon the individual crystal employed, and the type of crystal. It is known, for example, that silicon crystal rectifiers and germanium crystal rectifiers have opposite types of characteristic curves, one being of the type which bends upward as shown in Fig. 7, so that the crystal is operated near the heel of the curve, and the other being of the type which droops or bends downwardly so that the crystal is operated near the knee of the curve.

When the triple harmonic of the fundamental frequency is desired, a crystal multiplier may also be employed and the dimensions of the output transmission line may be so chosen as to cut-off the undesired lower frequencies, such as the fundamental frequency and the second harmonic, passing only the third harmonic. However, in order to increase the efficiency of the apparatus and avoid wearing out the crystal, when an odd harmonic is desired I prefer to employ a push-pull connection with two oppositely connected crystals, by means of which the second harmonic is inherently suppressed. For example, as illustrated in Fig. 3, a transmission line 51 may be employed having an input end 52 to which fundamental frequency energy is supplied, and an output end 53 at which an harmonic output is obtained.

The input portion of the line 51 is arranged as a double concentric circular transmission line with an inner concentric line 54 and an outer hollow cylindrical conductor 55, concentric with the line 54. The latter is adapted to be connected by conventional couplings to a similar type of concentric line (not shown) from which the input energy is received. The coaxial line 54 includes a hollow cylinder 56 and an inner conducting rod 57. The outer hollow cylinder 55 is tapered, as shown at 58, toward a point 59 at which it has a rectangular or oblong cross-section. Between the point 59 and the output end 53, the outer conductor 55 is in the form of a conventional rectangular wave guide, the dimen-

sions of which are so chosen that its cut off wavelength is slightly longer than the desired harmonic, for instance, the third harmonic of the energy supplied through the input concentric line 54. For example, the line 54 may be designed for 10 centimeter input and the wave guide output section 53 may be designed for 3.5 centimeters cut-off. For tuning the input end of the concentric line 51, a conventional slidable shorting plug 61 is provided, which includes an annulus 62 of conducting material making electrical contact with both the outer hollow cylinder 55 and the hollow cylinder 56.

For introducing the odd harmonic, a pair of nonlinear elements, such as crystal rectifiers 63 is provided. For supporting the crystal rectifiers 63 and enabling direct current bias connections to be made thereto, a pair of lateral coaxial lines 64 is provided, extending above and below the transmission line 51. The lines 64 may be similar in construction, each including an outer hollow cylindrical conductor 65 and an inner conducting rod 66. In order to provide for removability of the crystal rectifier 63, the outer cylinder 65 is removably attached to the outer conductor 55 of the transmission line 51. For example, a hollow projection 67 may be formed in the surface of the conductor 55 with the inside threaded to receive the lower exteriorly threaded end 68 of the hollow cylinder 65. For tuning the line 64, a shorting plug 33' may be provided similar to that described in connection with Fig. 1, or the shorting plug may include a single conducting hollow annulus 35 with a thin cylinder 69 of non-conducting material insulating the inner surface of the annulus 35 from the rod 66, so as to form a high frequency short, but preserve direct current insulation.

For making direct current connections the outer end of the line 64 is formed as a pin and socket connector including an outer screw threaded contact 74 electrically connected to the outer conductor 18 and a concentric pin contact 72 electrically connected to the conducting rod 66. For supporting the pin 72 in the outer end of the rod 66, an insulating bushing 73 is provided, and the annulus plug 35 serves to support the intermediate portion of the rod 66.

For supporting the crystals 63 laterally, insulating bushings 74 are provided, and for coupling the input end of the transmission line 51 to the transmission lines 64, a transverse internal conductor rod 75 is provided which is concentric with the transmission lines 64 forming a continuation of the inner rods 66, that is electrically and mechanically connected to the inner rod 57 of the transmission lines 54 and 51. The upper and lower ends of the rod 75 are drilled to form sockets for receiving the pin contacts of the crystal rectifiers 63 and the inner ends of the rod 66 are provided with contact buttons, as previously described, to make electrical contact with the crystal rectifier 63.

It will be understood that the portion of the lower transmission line 64, which has been broken away, is shown as turned 90° in Fig. 3, in order to show the slot 38 for receiving the pins 36.

The crystal rectifier 63 may be of the same type as represented by the crystal rectifier 17 of Fig. 1, except that one of the crystal rectifiers 63 is mounted in a non-standard position; that is, with reversed polarity. Biasing batteries (not shown) are connected to the upper and lower direct current contacts 71 and 72 for biasing the rectifiers 63 and the polarities of the biasing voltage are

made oppositely with respect to the inner conductors 66, so that each rectifier is biased in the same manner with respect to its own polarity.

Referring to Fig. 7, a third harmonic component of relatively great strength may be obtained from a square law crystal rectifier by a sufficiently large biasing voltage in the reverse (negative) direction so that the natural boundary layer is broken down and current flows in the reverse direction along the curve 77. The magnitude of the bias is such that the crystal operates around a voltage, represented by the vertical dotted line 78. The crystal is then forced to operate along the reversed portion 77 of its characteristic curve which has a relatively large third degree curvature. In order to avoid the necessity for care in preventing the crystal from being burned out and to increase stability two opposed crystals may be employed.

By employing two crystals of opposite polarity connected in push-pull, a stable third harmonic component of considerable strength is obtained. The composite push-pull characteristic curve is shown in Fig. 8. By selecting biasing voltages equalling the distances between the vertical axis I and the vertical lines 78 and 79, an inner portion of the characteristic curve between the lines 78 and 79 is effectively eliminated, and each crystal tends to operate with respect to one or the other of the lines 78 and 79 and the combination operates as if it had a characteristic curve represented by the curve lines 81 and 82, joined at the points 83 and 84.

If it is desired to mix or heterodyne one input circuit with another of a harmonic frequency, this may be done by employing a combination mixer multiplier, as illustrated in Fig. 5, for example. In this case, the fundamental frequency of a high frequency circuit, such as a three centimeter circuit, may be heterodyned with the third harmonic of a lower frequency input such as a 9 centimeter circuit. To this end, as shown in Fig. 5, an input wave guide 85, an input adjustable coaxial transmission line 86, and a coupling transmission line 87 may be employed, including a crystal rectifier element 88 for generating the third harmonic of the wave supplied through the coaxial line 86. For supplying the heterodyned output, a coaxial transmission line output coupling 89 may be provided.

The interconnecting transmission line 87 includes an outer hollow conductor 91, an inner cylindrical conductor 92, a suitable adjustable shorting stub device 93 for tuning, a contact device 94 for making an electrical connection with the upper or flat contact of the crystal rectifier 88. As shown, the inner conductor 92 is of relatively large diameter in comparison with the outer cylinder 91 and a narrow rod 95 is provided for joining the lower end of the conductor 92 to the crystal contact 94. The input coaxial transmission line 86 includes an outer hollow cylindrical conductor 97 and an inner conductor 98. For tuning purposes the outer conductor 97 may be in the form of a telescoping tube. For coupling the transmission line 86 to the transmission line 87 a T-probe 99 mounted within the cylinder 91 may be connected to the end of the inner conductor 98. The outer conductor 91 is removably joined to the top surface of the wave guide 85, by means of a suitable threaded extension 67 such as described in connection with Fig. 3.

The output transmission line connection 89 includes a hollow cylindrical member 101 electrically and mechanically joined to the lower surface

of the wave guide 85, an insulating bushing 102 supporting a connector socket 103 and an internally flanged tubular or cup-shaped member 104, threaded into the member 101 for supporting the insulator 102. The terminal 103 has a drilled opening 105 at the upper end serving as a socket contact for the lower pin terminal of the crystal rectifier 88 and has a connecting pin 106 extending downwardly through the insulator 102 and a suitable opening in the member 104. The member 101 is provided with flanges 107, thus forming with the pin or conductor rod 106, a suitable coupling of the type used for making connections with concentric transmission lines.

In order to avoid discontinuities in the wave guide 85, a quarter-wave trap 111 may be mounted around the socket terminal 105, spaced therefrom. Likewise, the contact member 94 may be provided with a tubular extension 112 forming a quarter-wave trap.

The righthand end of the wave guide 85 is closed by a suitable plug 108 which may be made adjustable, if desired, but which need not be adjusted if initially properly positioned to terminate the wave guide for the frequency of its input. For matching the apparatus to the wave-guide input, in order to avoid reflections and in order to obtain minimum standing wave ratio, adjustable tuning probes 109 may be provided which consist of rods with a suitable axially adjustable circuit of a conventional type for fixing the extent to which the rod extends into the wave guide 85.

I have herein shown and particularly described certain embodiments of my invention and certain methods of operation embraced therein for the purpose of explaining its principle of operation and showing its application, but it will be obvious to those skilled in the art that many modifications and variations are possible, and I aim, therefore, to cover all such modifications and variations as fall within the scope of my invention which is defined in the appended claims.

What is claimed is:

1. A microwave multiplier, comprising in combination a wave guide, a coaxial transmission line joined transversely to said wave guide, but having an inner conductor extending through said wave guide, a crystal rectifier in series with said inner conductor, and a connection for supplying fundamental frequency energy to said coaxial transmission line whereby a harmonic thereof is supplied to said wave guide.

2. Apparatus as in claim 1 including a source of direct current bias in series with said crystal.

3. A frequency multiplier comprising in combination, a transmission line with a fundamental frequency energy input connection and a harmonic energy output connection, transverse transmission lines joined to said first-mentioned transmission line, said last-mentioned transmission lines being of the coaxial type, each including a nonlinear circuit element and being coupled to the first-mentioned transmission line input.

4. A frequency multiplier comprising an electrically conducting member having a longitudinally extending conductor therein to form a coaxial input transmission line, and having an open portion forming a wave guide output transmission line, a pair of transverse transmission lines of coaxial type having inner conductors joined and extending through the first-mentioned conducting member, and electrically connected to the inner conductor of the input coaxial transmission line, and non-linear circuit

elements included in the inner conductors of the transverse transmission lines.

5. Apparatus as in the preceding claim including tuning adjustments for the coaxial transmission lines.

6. A mixer multiplier, comprising in combination a high frequency input transmission line, a low frequency input transmission line, a transmission line connecting the two, and a heterodyne output connection from said connecting transmission line, one of said lines including a nonlinear circuit element for introducing a harmonic of the input energy of the low frequency input transmission line.

15 7. A frequency tripler, comprising in combination an input transmission line designed for fundamental frequency input, an output transmission line coupled thereto, an interposed nonlinear circuit means for introducing harmonics, the output transmission line having such dimensions as to cut off wavelengths longer than the third harmonic of the fundamental frequency input.

20 8. A frequency multiplier, comprising a hollow electrically conducting member having a longitudinally extending conductor therein to form a coaxial input transmission line, and having an open portion forming a wave guide output transmission line, transverse transmission line means coupled to the input transmission line and nonlinear circuit means in said transverse transmission line means.

35 9. A mixer multiplier, comprising in combination a high frequency input transmission line, a low frequency input transmission line, interconnecting means extending therebetween, and nonlinear means in said interconnecting means for producing a harmonic of the frequency supplied through the low frequency input transmission line.

10. Apparatus as in the preceding claim, further including a heterodyne output connection for extracting heterodyne energy from said nonlinear means.

45 11. A microwave frequency multiplier comprising, in combination, a hollow pipe wave guide, a tubular conductor opening into said wave guide, a further conductor within said tubular conductor forming a coaxial transmission line therewith and extending transversely across said hollow pipe wave guide, a crystal rectifier connected in series with said further conductor, means for supplying ultra high frequency energy to said crystal rectifier, and means for tuning said coaxial line to control the current distribution along the portion of said further conductor extending across said wave guide.

55 12. A microwave frequency multiplier comprising, in combination, a hollow pipe wave guide, first and second tubular conductors connected to said wave guide and extending in opposite directions therefrom, a further conductor extending through said first tubular conductor, said wave guide and said second tubular conductor and forming with said tubular conductors, first and second coaxial transmission lines coupled to said wave guide, a crystal rectifier in series with said further conductor, means for applying to said crystal rectifier ultra high frequency energy of a wavelength longer than the cut-off wavelength of said wave guide, movable means within said first coaxial line for providing an adjustable ultra high frequency energy conducting path between said first tubular conductor and said further conductor, and movable means within said sec-

ond coaxial line for providing an adjustable ultra high frequency energy conducting path between said second tubular conductor and said further conductor.

13. A microwave frequency multiplier as defined in claim 12, further including means for applying direct bias voltage to said crystal rectifier for varying the operating characteristics thereof whereby the frequency multiplication efficiency of said frequency multiplier may be enhanced.

14. A microwave frequency multiplier comprising a hollow pipe wave guide, first and second tubular conductors connected to said wave guide and extending in opposite directions therefrom, a further conductor extending through said first tubular conductor, said wave guide and said second tubular conductor and forming with said first and second tubular conductors, first and second coaxial transmission lines coupled to said wave guide, a first crystal rectifier positioned within said first tubular conductor and connected in series with said further conductor, a second crystal rectifier positioned within said second tubular conductor and connected in series with said further conductor, means for applying to said further conductor intermediate said first and second crystal rectifiers ultra high frequency energy of a wavelength longer than the cut-off wavelength of said wave guide, movable means in said first tubular conductor for providing an ultra high frequency current path between said first tubular conductor and said further conductor, and movable means in said second tubular conductor for providing an ultra high frequency current path between said second tubular conductor and said further conductor.

15. A microwave frequency multiplier as defined in claim 14, further including means connected to said further conductor for applying direct bias potential to said crystal rectifiers.

16. A microwave frequency multiplier comprising, in combination, a wave guide, a tubular conductor opening into said wave guide, a further conductor within said tubular wave guide forming a coaxial transmission line therewith and extending transversely across said wave guide, a crystal rectifier connected in series with said further conductor, means for supplying to said crystal rectifier ultra high frequency energy of a wavelength longer than the cut-off wavelength of said wave guide to produce harmonic currents in said transmission line, means for tuning said coaxial transmission line to regulate the harmonic currents therein, and means for applying a direct bias potential to said crystal rectifier for enhancing the harmonic operation thereof.

17. Apparatus as recited in claim 16, further including movable ultra high frequency current conducting means positioned within said coaxial transmission line for varying the ultra high frequency current distribution along said further conductor, whereby high intensity har-

monic energy coupling is provided between said further conductor and said wave guide.

18. A microwave frequency multiplier comprising a hollow pipe wave guide, a conductor extending transversely through said wave guide, tubular conducting means connected to said wave guide and forming an outer conductor for co-operation with said first conductor as a coaxial transmission line, means for applying to said first conductor ultra high frequency energy of a wavelength longer than the cut-off wavelength of said wave guide, a first crystal rectifier connected in series with said conductor in a first current-carrying orientation, and a second crystal rectifier connected in series with said conductor in an opposite current-carrying orientation for conduction of current during opposed half cycles of the applied ultra high frequency energy.

19. Ultra high frequency apparatus comprising first and second coaxial line elements connected together at a junction point, means for producing an ultra-high frequency potential difference between the inner conductors of said coaxial line elements and the outer conductors thereof at said junction point, and an energy utilization device coupled to said coaxial line elements at said junction point and responsive to ultra-high frequency currents in the inner conductors of said first and second coaxial line elements.

20. Ultra high frequency apparatus comprising first and second coaxial line elements connected together at a junction point, a third coaxial line joining said first and second coaxial line elements at said junction point, the inner conductor of said third coaxial line being connected to the inner conductors of said first and second coaxial line elements at said junction point, and a wave guide adjoining said first and second coaxial line elements at said junction point and coupled to the inner conductors thereof, whereby said wave guide is coupled to said third coaxial line through electromagnetic coupling between said wave guide and the inner conductors of said first and second coaxial line elements.

21. Ultra high frequency apparatus comprising a hollow pipe wave guide having first and second openings therethrough, first and second tubular conductors connected to said wave guide at said openings, a third conductor extending through said first tubular conductor, said wave guide and said second tubular conductor and forming first and second transmission lines with said first and second tubular conductors, and a fourth conductor connected to said third conductor at a point between said first and second transmission lines, whereby said fourth conductor is coupled to electromagnetic energy guided through said hollow pipe wave guide in accordance with the difference of impedance to current flow through said first and second transmission lines.

EDWARD L. GINZTON.
